Primary Examiner—Gary D. Watson*Assistant Examiner*—Susan Bennett Hattan(74) *Attorney, Agent, or Firm*—Hoffmann & Baron, LLP(57) **CLAIM**

The ornamental design for a rework bracket for electrical outlet boxes, as shown and described.

DESCRIPTION

FIG. 1 is a top perspective view of a rework bracket for electrical outlet boxes showing our new design;

FIG. 2 is a side perspective view thereof;

FIG. 3 is a bottom perspective view thereof;

FIG. 4 is a first side view thereof;

FIG. 5 is a bottom view thereof;

FIG. 6 is a second side view thereof; and,

FIG. 7 is an end view thereof, drawn at a larger scale.
